UNITED STATES PATENT OFFICE.

ROBERT A. MAHAN, OF JONESBORO, ARKANSAS, ASSIGNOR OF ONE-HALF TO WILLIAM J. BAKER, OF NEWPORT, KENTUCKY.

FIXTURE FOR ELECTRIC INCANDESCENT LAMPS.

1,193,579.

Specification of Letters Patent. Patented Aug. 8, 1916.

Application filed August 30, 1915. Serial No. 48,011.

To all whom it may concern:

Be it known that I, ROBERT A. MAHAN, a citizen of the United States, residing at Jonesboro, in the county of Craighead and State of Arkansas, have invented certain new and useful Improvements in Fixtures for Electric Incandescent Lamps, of which the following is a specification.

My invention relates to fixtures for electric incandescent lamps designed to be portable.

It is the object of my invention to provide an electric incandescent lamp with a portable support of novel construction, so arranged that it may be employed as a stand, for instance upon a table, as a hanging bracket supported by a suitable object, as a mirror frame, the apron of a roll-top desk, a pole, a nail, or in other suitable arrangement, and so arranged that the rays of light may be directed in desired directions; further to provide novel means for adjusting the axis of the light-bulb to desired inclination with relation to the support and about an axis substantially perpendicular to the support; and, further, to provide novel means for adjusting and supporting the light-shade.

The invention will be further readily understood from the following description and claims, and from the drawings, in which latter:

Figure 1 is a perspective view of my improved device, showing the same employed as a stand, with the shade inclined, and the movable member of the shade in partly closed position. Fig. 2 is a perspective view of my improved device showing the same supported by two of its legs. Fig. 3 is a perspective view of the same, supported from the curtain of a roll-top desk by means of its clamp-arm. Fig. 4 is a perspective view of the same, supported from a rod by means of its clamp-arm. Fig. 5 is a perspective view of the same, supported from a nail. Fig. 6 is a vertical axial section of my improved device. Fig. 7 is a bottom view of the same, the legs being partly broken away. Fig. 8 is a perspective view of the stand members shown in separated relation. Fig. 9 is a sectional detail view on the line 9-9 of Fig. 7. Fig. 10 is a cross-sectional view on the line 10-10 of Fig. 6, showing the manner of mounting the bases of the shade members. Figs 11 and 12 are enlarged sec-

tional detail views taken on the same section line as Fig. 6. Fig. 13 is a sectional detail view of the socket-joint, taken on the line 13-13 of Fig. 6. Fig. 14 is a detail in cross-section on the line 14-14 of Fig. 6, showing the spring means for the clamp-arm, and Fig. 15 is an enlarged perspective view, partly in section on the line 15-15 of Fig. 6, showing the preferred cross-sectional form of the legs and clamp-arm.

The support of the lamp is shown generally at 11, and in the present exemplification comprises a plate 12 of general triangular form having cheeks 13. Legs 14, 14 and 15 extend from the cheeks and are preferably riveted thereto by rivets 17. The legs 14, 14 are preferably mates and extend divergently from the plate. They are of general bow form, the feet 18 thereof extending toward the perpendicular axis of the plate. The leg 15 is preferably longer than the leg 14 and less bowed than the latter, the foot 19 thereof projecting inwardly toward the perpendicular axis of the plate and having a hole 20.

The inner faces of the legs 14 are preferably provided with cushion-strips 21, for instance of felt, which at their lower ends are bent backwardly under the feet 18. The leg 15 is also preferably provided with an inner cushioning strip 22, which is laid lengthwise of the upper face of the foot 19 and reversely bent below said foot. In this manner a cushion for the inner face of each of the legs and under the foot of each of the legs is provided, so that contact may be made along said faces and by said feet with furniture or other objects without danger of disfigurement of the same.

A clamp-arm 25 extends lengthwise of the leg 15 and is pivoted to the support. Pivot lugs 26 are struck up from the plate 12 and pivot lugs 27 are struck down from the clamp-arm 25, a pivot-rod 28 being received through said lugs and held in place, as by riveting the ends thereof. A helical spring 29 surrounds the rod, one end 30 thereof bearing against the inner end of the clamp-arm and the other end 31 thereof bearing against the plate for normally urging the clamp-arm toward the leg 15. The clamp-arm is of general hook form. The inner face of the clamp-arm is provided with a cushion lining 32, as of felt, the outer end of the felt being received about the outer

end of the clamp-arm as shown at 33, so that any object with which the clamp-arm may come in contact, as by being received about the same or having its end made contact therewith, will have the cushion thereagainst for preventing damage or scratching.

The clamp-arm and the legs may, if desired, in order to strengthen the same, be provided with longitudinally extending ribs 34, 35 (see Fig. 15), these ribs being struck up from the metal of the clamp-arm and legs and extending approximately the full length of said arm and legs.

The plate is at its middle provided with a flange 41, which is shown as an annular flange forming a bearing. A tubular pivot-member 42 is journaled in said bearing and is preferably held to the bearing in adjusted positions for maintaining the tubular pivot-member in the position to which it may be adjusted with relation to the support 11. The tubular member has a portion thereof bent outwardly for forming a bearing upon the bearing-plate, shown as an annular bead 43 bearing upon the flange 41.

A retaining piece 44 is received about the tubular member at the other side of the plate and is arranged to rotate therewith. It is shown as a spring-plate having an aperture 45 therein, the wall of which forms a bearing about the lower end of the tubular pivot-member. The wall of the aperture is shown provided with notches 46. When the tubular member has been received through the flange 41 and the retaining piece, the lower end of the tubular member is spread into the notches 46, as shown by the projections 47.

The retaining-piece is exemplified as a spring-plate provided with spring-feet 48 shown curved toward the plate 12, the plate and spring-feet being provided with coacting projections and depressions, exemplified by the toes 49 on the spring-feet 48 and notches formed in said plate. These notches are exemplified as formed by radially extending teeth extending about the bearing in the plate 12 as an annular rack 50.

The plate 12 is provided with a recess 51, the face of the upper wall of which is provided with the rack, the retaining-piece being received in said recess. The retaining-piece acts to hold the tubular pivot-member in its bearing, with the annular bead 43 pressed toward the flange 41 and the toes 49 pressing into the depressions between the teeth of the rack, so that when the tubular pivot-member is moved about its axis of rotation it will be maintained automatically in its adjusted positions.

The electric light-bulb is shown at 55, the plug thereof being arranged to be received in a socket 56 having connection with a socket pivot-member 57, as shown by the threaded connection 58 and set-screw 59.

The pivot-member 57 is provided with a bore 61 extending axially with relation to the light-bulb and having a lateral opening 62 adjacent to the pivot of the pivot-member 57. The electric conductors 63, 64, which connect with the terminals of the light-bulb, are received through this bore, the bore being sufficiently large to also receive the insulating covering of said conductors.

The tubular pivot-member 42 is provided with a fork, the tines 68, 69, of which are formed out of the metal of the tube by having opposite walls of said tube pressed toward each other, as shown at 70, the tines being separated by the slots 71 in said metal. The socket pivot-member is provided with a coacting cheek 73 which is received between the tines 68, 69. The tines and cheeks are provided with pivot apertures through which a pivot screw 74 extends. The head 75 of the screw is arranged to be pressed toward one of said tines, a thumb-nut 76 received about the threaded end of said screw being arranged to be pressed toward the outer face of the other of said tines, when said thumb-nut is turned manually, for clamping said cheek between said tines, and thereby holding the light-bulb at the inclination in which it has been adjusted by swinging the socket pivot-member upon the support.

79 is a bearing-piece for a lamp-shade, and is arranged to rotate about the socket, as by having an inner annular flange 80, which is received between an annular bead 81 and the outer annular spread end 82 of the socket.

A shade is provided which is composed of the sections 83, 84. The shade-section 83 is instanced as the fixed shade-section being fixed to the bearing-piece 79. This bearing piece has an inwardly extending annular bead 86, the shade section 83 having a coacting bead 87 received about the annular bead 86, and is rigidly secured in place as by being soldered thereto. The shade-section 84 is arranged to be moved about the axis of the light-bulb with relation to the shade-section 83. The shade-section 83 forms the outer half and the shade-section 84 the inner half of the shade, which may be adjusted so as to close the shade about the light. In order to provide for such movement by simple and economical means and in such manner that the proper relation between the shade-sections for forming a continuous shade of preferably pear-shape or other form may be provided, irrespective of the relative positions between the shade-sections 83 and 84, I have provided the following instrumentalities: At the outer ends of said shade-sections they are connected by a pivot 89, shown accomplished by a thimble 90 received through holes in the upper ends of said shade-sections in substantially the line of 125

the axis of the light-bulb and the axis of rotation of the bearing-piece 79. This thimble has a washer 91 received thereabout between the upper ends of said shade-sections, 6 the ends of said thimble being spread as shown at 92, 93, respectively across the outer face of the outer shade-section and the inner face of the inner shade-section for holding said parts in pivoted relation.

10 The base of the shade-section 84 is arranged to bear against the coacting beads 86, 87 and is preferably provided with a shoulder 96 coacting with the bead 87. A spring 97 normally urges said base of said shade-section 84 against said beads. The spring is shown as received through eyes 98, 99, in the base of the shade-section 84 and bears against the opposite face of the bearing-piece 79 for normally pressing the 20 base of the shade-section 84 against its bearing face. The ends 101 of the spring are preferably curved inwardly (see Fig. 10,) so that they may readily pass the edges of the base of the shade-section 83. The ends of 25 the springs and their adjacent portions are received in the annular groove 102 formed in the bearing-piece 79 and the corresponding portion of the shade-section 83. The construction is such that the movable shade-section is maintained in true relation with the relative stationary shade-section.

The peripheral edge of the outer shade-section is preferably outwardly flared, as shown at 103, and the relatively movable shade-section is provided with a laterally extending finger-piece 104.

The shade-section can be relatively moved about the axis of the light-bulb for providing the desired light opening between the 40 shade-sections, in the present instance representing any sector up to one-half of the circle about the light-bulb, and this opening, if desired, may be reduced to a small slit of light-opening, so that either a narrow or a 45 wide opening may be provided, and this opening is shiftable about the axis of the lamp by the turning of the bearing-piece 79 about the lamp-socket, for causing the projection of the light in any desired direction.

50 The inner face of the shade-sections may be provided with a light reflecting or mirror surface for projecting the light.

I have, in Figs. 1 to 6, inclusive, of the drawings, instanced various uses for which 55 the device may be employed. The multiplicity of uses of my improved device is exemplified in said figures, but the device is not restricted to the uses therein shown. The various positions and relations in which 60 the light-bulb may be employed are readily attained by rotating the base pivot-member on the support, thereby swinging the lamp-socket around the support so as to extend in different radial positions therefrom, and by 65 swinging the socket pivot-member upon the

tubular pivot-member so as to project at different inclinations with relation to the plane of the support, the shade-sections being moved about the longitudinal axis of the light-bulb in any of the adjusted positions of the lamp-socket for projecting the light in the desired direction and to the desired width. 70

One of the advantages of my improved device is that its various parts, with possibly 75 the exception of the socket pivot-member, may be formed out of sheet metal for providing a cheap, light and strong and readily assembled structure.

Having thus fully described my invention, 80 what I claim as new and desire to secure by Letters Patent, is:

1. A portable fixture for electric incandescent lamps, comprising in combination a support provided with a bearing, a pivot-member journaled in said bearing, said bearing provided with a flange extending laterally therefrom, a spring-plate secured to rotate with said pivot-member, said spring-plate provided with radially extending separated spring-fingers extending outwardly beyond said bearing, said spring-fingers and flange provided with coacting tooth and notch means pressed one toward the other by said spring-fingers for maintaining said pivot-member in adjusted positions, and a socket pivot-member pivoted to said first-named pivot-member arranged for receiving an electric incandescent light-bulb, whereby said first named pivot-member is arranged to rotate on said support and said socket pivot-member is arranged to swing on said first-named pivot-member, for adjusting the light-bulb to inclination and angular position with relation to said support. 95 100

2. In a portable fixture for electric incandescent lamps, the combination of a socket pivot-member, a socket for an electric incandescent light-bulb thereon, an annular bearing-piece mounted to revolve on said socket, and a pair of shade-sections comprising an outer shade-section and an inner shade-section, said shade-sections having bases, one of said bases having bearing upon the other of said bases, one of said bases 110 fixed to said annular bearing-piece, both said bases arranged annularly with relation to said annular bearing-piece, and said shade-sections pivoted together at their ends opposite their bases by a pivot in substantial 115 line with the longitudinal axis of the light-bulb received in said socket.

3. In a portable fixture for electric incandescent lamps, the combination of a socket pivot-member, a socket for an electric 120 incandescent light-bulb thereon, an annular bearing-piece mounted to revolve on said socket, and a pair of shade-sections comprising an outer shade-section, an inner shade-section, said outer shade-section fixed to said 125 130

- 4
- annular bearing-piece, the base of said inner shade-section having bearing in the base of said outer shade-sections and said annular bearing-piece, and said shade-sections pivoted together at their ends opposite their bases by a pivot in substantial line with the longitudinal axis of the light-bulb received in said socket.
4. In a portable fixture for electric incandescent lamps, the combination of a portable support comprising a plate and legs extending divergently therefrom comprising a pair of legs whose lower ends are curved inwardly toward the perpendicular axis of said plate and a third leg of less curvature, and a clamp-arm pivoted at the inner end of said third leg and being of bowed form and extending lengthwise of said third leg and coacting therewith for clampingly supporting said support.
5. In a fixture for an electric incandescent lamp, the combination of a light-bulb socket, an annular bearing-piece about said socket, a shade-section having its base fixed to said bearing-piece, said bearing-piece and the base of said shade-section provided with an inner annular groove, an inner similarly shaped shade-section, said shade-sections pivoted together at their outer ends in substantially the line of the longitudinal axis of said socket, and a spring extending from the base of said inner shade-section and movable in said groove in said annular bearing-piece and the base of said outer shade-section, and said inner shade-section arranged to be moved laterally within and outwardly from said first-named shade-section.
6. In a portable fixture for electric incandescent lamps, the combination of a supporting member provided with a central upward bulge provided with a central bearing, the upper wall of said bulge forming a laterally extending annular flange about the said bearing, a tubular pivot-member received in said bearing, the tube of said pivot-member provided with an annularly arranged bead resting on said bearing, a spring-plate provided with radially extending separated spring-fingers projecting toward said annular flange and bearing thereagainst, said spring-plate fixed to the lower end of said tubular pivot-member, said spring-fingers arranged for pressing said bead toward said bearing and so that said tubular pivot-member is maintained in adjusted positions about its axis of rotation, a socket pivot-member pivoted to said tubular pivot-member arranged for swinging to inclinations with relation to said axis, and a socket for an electric light-bulb on said socket pivot-member.
- In testimony whereof, I have hereunto signed my name in the presence of two subscribing witnesses.
